United States Patent Office.

JOHN C. DELL, OF PHILADELPHIA, PENNSYLVANIA.

Letters Patent No. 71,588, dated December 3, 1867.

IMPROVEMENT IN SCALES.

The Schedule referred to in these Letters Patent and making part of the same.

TO ALL WHOM IT MAY CONCERN:

Be it known that I, JOHN C. DELL, of Philadelphia, Pennsylvania, have invented an Improvement in Scales; and I do hereby declare the following to be a full, clear, and exact description of the same.

My invention consists of a scale in which a single graduated beam is connected both to a "platform" and to a "scoop," as fully described hereafter, so that the weight of articles placed either on the platform or in the scoop will be indicated on the said beam, without the necessity of adjusting any part of the scale.

In order to enable others skilled in the art to make and use my invention, I will now proceed to describe its construction and operation, reference being had to the accompanying drawing, which forms a part of this specification, and in which—

Figure 1 is an end elevation, partly in section, of my improved scale.

Figure 2, a plan view, partly in section, the platform of the scale being removed.

Figure 3, a sectional elevation on the line 1-2, fig. 1; and

Figure 4, a section on the line 3-4, drawn to an enlarged scale.

A is the base of the scale, at one end of which is a hollow standard, *a*, and from the opposite sides of the latter project arms *b b c c*. At the sides of a graduated beam, B, are knife-edged projections, which rest on bearings on the arms *b b*, and between the arms *c c* is suspended a rock-frame, F, sharp-edged projections at the sides of which rest on bearings in the said arms, a part of the frame having a sharp lower edge, and bearing in a clevis, *f*, connected to the beam B. From the long arm of this beam B are suspended the usual weight-holder D and adjustable weight C, and on a screw at the opposite end of the beam turns the ordinary adjustable balance-weight E. Through a clevis, G, which is hung to sharp-edged projections at the sides of the frame F, passes a rod, H, fig. 4, the upper end of which extends into a hollow projection at the junction of the four arms of a frame, I, the said projection resting on the clevis G, and extending through an opening in the beam B, without touching the latter. In the frame I rests the usual detachable "scoop" N, and to the lower end of the rod H is connected a link, *k*, which is jointed to a projection at the side of the base A, so that the said rod is maintained in a vertical position without the freedom of its vertical movements being interfered with. In links *i*, suspended from the base, A, rest sharp-edged projections at the sides of two levers, *k k'*, a sharp-edged projection at the inner end of the lever *k'* resting in a clevis, *d*, suspended from the lever *k*, and to the end of the latter, which projects beneath the standard *a*, is jointed a rod, *m*, the upper end of which is connected to a clevis, *n*, suspended from the beam B. From the sides of the levers *k k'* project knife-edged bearings *o o*, on which rest projections *p p* at the under side of a platform, L, the latter extending over an opening in the frame A, above the said levers.

When material to be weighed is deposited in the scoop N, the rock-frame F is depressed, and, bearing on the link *f*, raises the long arm of the beam B, on which the weight C is adjusted as usual. In like manner, an article placed on the platform L, depresses the latter, and the levers *k k'*, draws down the rod *m*, and thus elevates the long arm of the beam, so that the weight of an article placed in the scoop will be as quickly and accurately indicated on the beam B as if it were placed upon the platform, while it is not necessary to adjust or remove any portion of the scale prior to placing a substance to be weighed on one part or the other. The scale may, therefore, be employed for ascertaining the weight of solid or bulky articles, for the reception of which the platform is adapted, or of powders, granulated substances, etc., which may be best retained by the scoop.

I do not claim broadly the combination of a graduated beam, a scoop, and a platform, so that the weight of an article placed either upon the platform or in the scoop will be indicated on the beam; but

I claim as my invention, and desire to secure by Letters Patent—

A graduated beam B, connected to levers supporting a platform, L, in combination with a lever, F, which supports a "scoop," N, and which is connected to the beam B, the whole being constructed and operating substantially as and for the purpose described.

In testimony whereof, I have signed my name to this specification in the presence of two subscribing witnesses.

JOHN C. DELL.
